Attest,

UNITED STATES PATENT OFFICE.

OSCAR W. ANDERSEN, OF OAK PARK, ILLINOIS, ASSIGNOR TO PETTIBONE MULLIKEN COMPANY, A CORPORATION OF NEW YORK.

CHAIN-EQUIPPED STRUCTURE.

Application filed October 27, 1927. Serial No. 229,139.

My invention relates to structures, such as dredges and the like, and particularly suction dredges, which operate in material containing loose rock and comprising as elements thereof movable chains between the pivoting pins of which and guide devices for the chains rocks sometimes become wedged in the operation of the structures and impair the operation of the machines.

My primary object is to provide means whereby the wedging of rocks between the chains and the guides referred to will not impair the pins forming the pivotal connections between adjacent links of the chains.

Referring to the accompanying drawings:—

Figure 1 is a view in side elevation of the suction-pipe-equipped arm of a suction dredge embodying my improvements. Figure 2 is a plan view of a portion of the chain screen forming an element of the dredge. Figure 3 is a view in side elevation of the structure shown in Fig. 2. Figure 4 is an enlarged section taken at the line 4—4 on Fig. 1 and viewed in the direction of the arrows. Figure 5 is an enlarged section taken at the line 5—5 on Fig. 2 and viewed in the direction of the arrows. Figure 6 is a broken sectional view taken at the line 6 on Fig. 5 and viewed in the direction of the arrow; and Figure 7, a broken plan sectional view taken at the line 7 on Fig. 6 and viewed in the direction of the arrow.

The particular construction of suction dredge in connection with which I have chosen to illustrate my invention, comprises an arm 8 preferably made up of truss members, struts and braces to afford the desired rigidity of structure, the upper end of the arm 8 being pivoted at 9 to any suitable support 10 so that its lower end may be raised and lowered as desired. The means for raising and lowering the lower end of the arm are not shown as they are in common use and form no part of the present invention.

The arm 8 carries the usual suction pipe 11 and suitable means (not shown) are provided at the upper end of this pipe for sucking water and material to be dredged, upwardly through this pipe in the usual manner. The lower end of the pipe 11 terminates in a nozzle 12 presenting a downwardly opening flared mouth.

The machine also comprises a traveling screen chain 13 of the link and pivoting pin

type, the upper end, or bight, of the chain being carried on a driving sprocket 14 which may be driven in any suitable way, as for example by means of the gears 15, 16, 17 and 18 forming a train which may be actuated by any suitable source of power, as for example a motor or engine. The lower end of the chain which extends across the mouth of the nozzle 12 is supported at its opposite edges on a pair of disk wheels 19 located at opposite sides of the nozzle 12 and mounted on a shaft 20 secured in triangular plate members 21 provided in spaced apart relation on the lower end of the arm 8, the wheels 19 having flanges to retain the chain against lateral displacement thereon. The chain screen thus supported serves as a screen or sieve for the mouth of the nozzle 12 for preventing entrance thereto of undesired objects as for example rocks.

The arm 8 is provided with upper longitudinally extending angle irons 22 the lower flanges 23 of which form a support for the upper reach of the chain, and the upwardly extending flanges 24 of which serve as guides preventing lateral displacement of the chain; and is also provided with channel guides 122 in which the lower reach of the chain screen is supported and guided.

Referring now to the particular construction of the screen chain illustrated, it is formed of a series of links each shown as comprising link bars 25, 26, 27, 28 and 29, (five of these link bars being shown but without any intention of limiting the invention thereto), and pivotal connecting pins 30 connecting together adjacent, overlapped ends of the link bars. The link bars referred to are formed with deflected ends, as shown, at which portions adjacent ends of the link bars overlap and receive the pins 30, with rollers 31 located between the sets of bars 25 and 26 and 28 and 29 and journalled on the pivoting pins 30. The rollers 31 are shown as journalled on the opposed reduced end portions 25^a, 26^a, 28^a, and 29^a of the link bars 25, 26, 28 and 29, and spacer sleeves 32 surround the pivot pins 30 between the link bars 26 and 27 and 27 and 28. The pivoting pins 30 are held in assembled relation with the link bars and spacers described, by washers 33 preferably made of steel and of general U-shape which are applied to straddling position about the peripherally grooved portions 34 of the pins and then bent at their leg portions 37^a into the po-

sition shown in Fig. 6 to hold them against disengagement from the pins, these washers coacting with the headed ends of the pins and with the adjacent link bars 29 affording great resistance against shearing in the event of force being applied against the end of the pins in a direction lengthwise of the latter.

The screen chain also comprises projecting hooks, claws or fingers 26^a and 28^a which serve to dig into the material to be excavated, to loosen up, agitate, and stir up the material, for permitting the suction in the pipe 11 to more readily carry the material away. These claws, hooks or fingers 26^a and 28^a are shown as formed integrally with certain of the link bars 26 and 28, respectively, and also serve to engage and remove away from the mouth of the nozzle 12 objects which are too large to enter the latter, these objects being thrown to one side by these hooks or carried upwardly on the chain and dumped on the upper end as the chain passes over the upper sprocket.

The provision of the guide devices 22 and 122 presents the possibility of rocks becoming wedged in between the sides of the screen chain and the walls of these guide-devices and which, if force is applied by the wedging action against the pins in a direction laterally thereof, is likely to shear off the pins and thereby impair the machine for properly functioning.

I have, therefore, in accordance with my invention provided means whereby should rocks become wedged, in any direction, between the chain screen and the walls of these guide-devices or either of them, the ends of the pins 30 will not be subjected to undue force exerted laterally against them but this force will be taken by another member in such a way as not to unduly stress the pins.

In accordance with the preferred illustrated embodiment of my invention the wedging force referred to is caused to be taken by the link bars 29 which, to this end, are provided on their outer faces with bosses 35 in alignment with the pins 30 and forming housings therefor with openings 36 to receive the pins 30 in the assembling operation, the outer faces of these housings preferably extending slightly beyond the extreme outer end portions of the pins 30 and completely peripherally surrounding the latter, as shown.

The openings 36 through the housings are preferably enlarged at their inner ends as represented at 37 and open upwardly and downwardly as represented in Fig. 6 to permit of the ready application of the washer 36 to place and the deforming of the latter into holding position.

It will be understood from the foregoing description that the pins 30 are protected against direct engagement therewith of rocks that may become wedged between the chain and the guide devices. The portions of the chain screen against which the wedging ac-

tion would be exerted may be made sufficiently heavy to resist the force of such wedging action without danger of impairing any of the parts, and even to such an extent as to stop the means for driving the chain screen, it being desirable to provide a yieldable safety connection (not shown) between the source of power and the chain screen which will yield before sufficient resistance is presented by the wedging of the chain screen as stated, as to stall the power device, particularly if an electric motor.

While the housings 35 are shown as completely surrounding the ends of the pins 30 peripherally it is not necessary, in carrying out my invention, that the housings entirely surround the pins, it being sufficient if the housings extend adjacent those surfaces only of the pins against which the wedging action could be exerted by stones engaging the chain screen.

While I have illustrated and described a particular construction embodying my invention, I do not wish to be understood as intending to limit it thereto as the same may be variously modified and altered without departing from the spirit of my invention.

What I claim as new, and desire to secure by Letters Patent, is:

1. In a machine of the character set forth, the combination of a chain mounted to be moved and formed of links and pins pivotally connecting said links together, and housings on ends of certain of said links and completely surrounding said pins peripherally for protecting the ends of the latter and means inwardly of the ends of the pins for maintaining the pins and links in operative relation.

2. In a machine of the character set forth, the combination of a chain mounted to be moved and formed of links and pins pivotally connecting said links together, guide means for a reach of said chain and comprising members along which said chain travels, and means for preventing stones which may become wedged in any direction between said chain and one of said members from exerting force against said pins laterally thereof by direct contact with the latter comprising housings at the ends of said pins peripherally surrounding said ends, said housings inwardly of said ends having openings, and means for maintaining the pins and associated parts in place applicable through said openings.

3. In a machine of the character set forth, the combination of a chain mounted to be moved and formed of links and pins pivotally connecting said links together, guide means for a reach of said chain and comprising members along which said chain travels, and means for preventing stones which may become wedged in any direction between said chain and one of said members from exerting force against said pins laterally thereof by

direct contact with the latter, comprising housings on certain of said links at the ends of said pins peripherally surrounding said ends, said links inwardly of said ends having openings and means for maintaining the pins and associated parts in place applicable through said openings.

5. In a machine of the character set forth, the combination of a chain mounted to be moved and formed of links and pins pivotally connecting said links together, guide means for a reach of said chain and comprising

ing members along which said chain travels, and means for preventing stones which may become wedged between said chain and one of said members from exerting force against said pins laterally thereof by direct contact with the latter comprising apertured housings on ends of certain of said links and completely peripherally surrounding the ends of said pins and means inwardly of said ends of the pins for maintaining the latter and associated parts in place.

OSCAR W. ANDERSEN.
